UNITED STATES PATENT OFFICE.

GEORGE E. MUSGROVE, OF WILKINSBURG, PENNSYLVANIA, ASSIGNOR TO GENERAL ELECTRIC COMPANY, A CORPORATION OF NEW YORK.

GAGE FOR TANKS.

No. 881,607.

Specification of Letters Patent. Patented March 10, 1908.

Application filed September 17, 1906. Serial No. 334,895.

To all whom it may concern:

Be it known that I, GEORGE E. MUSGROVE, a citizen of the United States, residing at Wilkinsburg, county of Allegheny, 5 State of Pennsylvania, have invented certain new and useful Improvements in Gages for Tanks, of which the following is a specification.

This invention relates to gages for indicating the level of liquid in a tank. It is especially designed for use on a transformer oil tank, but is applicable to any receptacle in which it is desirable to maintain the liquid contents at a given level. In an oil-cooled 10 transformer, the loss of oil is not readily detected, because the top of the tank is closed. It is, however, essential to the safe working of the transformer that the level of the oil shall not fall low enough to expose 15 the windings. Ordinary glass gage-tubes have been attached to transformer tanks, but it is difficult to make an oil-tight joint at the points where the gage-tube fittings pass through the wall of the tank. In order to 20 avoid this trouble, the present invention utilizes the principle of the siphon, and consists of a gage-tube connected at its lower end with an inverted U-shaped tube which straddles the upper edge of the tank and is 25 filled with oil. The lower end of the leg inside the tank is turned upwardly to prevent all the oil in the device from escaping 30 from the gage in case the tank is emptied. When the oil in the tank rises above the up- 35 turned end of the inner leg, a certain amount of oil flows from the inner leg to the outer, and the oil in the gage tube rises to the same height as that in the tank, so that any 40 variation of level in the tank is accurately indicated in the tube.

In the accompanying drawing, Figure 1 is a side elevation of a transformer tank equipped with my improved gage, and Fig. 2 is a sectional elevation of the gage, on a 45 larger-scale.

The tank 1 is of the usual construction: the coils of the transformer being shown at 2. The normal level of the oil is at about the line 3. The glass gage tube 4 is incased in a 50 metal sleeve 5, cut away to expose the tube and screwed into a coupling 6 at its lower end. A screw plug 7 is tapped into the upper end of the sleeve and clamps the gage-tube endwise; suitable packing 8 being 55 interposed between the ends of said tube.

and the coupling and plug. A vent hole 9 is drilled through said plug. A siphon tube in the form of an inverted U connects the gage-tube with the tank. Both legs of the U are preferably of the same length, and the 60 lower end of one leg 10 communicates with the coupling 6, while the lower end of the other leg 11 is turned up in a loop 12 for a short distance.

In or near the upper edge of the tank 1 above the level of the liquid is a notch or opening through which passes the bight of the siphon, so that the leg 10 and the gage-tube 4 hang outside the tank, while the leg 11 depends into the tank. The siphon tube is 65 filled with liquid, so that the rise and fall of the liquid in the tank causes a similar variation in the column of liquid in the gage-tube, which thus indicates at all times the height of the contents of the tank. The 70 gage-tube and the siphon tube are long enough to extend a suitable distance above and below the normal level of the liquid in the tank, so that said liquid can fall below the safety line before it reaches the lower 75 limit of the gage-tube. This limit is determined by the upturned end of the inner leg of the siphon. When the tank is emptied, the liquid in the gage-tube will drop to the level of the upturned end of the loop 12, but 80 no farther, so that the gage is always in condition to operate when the tank is filled again. If the loop 12 is omitted, the device 85 will automatically empty itself when the liquid in the tank falls below the end of the 90 inner leg 11 and must be refilled before it can be used.

In the drawing, the gage-tube is shown extending up as high as the bight of the siphon, but this is not essential, as the gage-tube need be only long enough to show the permissible variations of level, while the siphon must be high enough to be at all 95 times above the highest possible level, and thus it preferably straddles the upper edge 100 of the tank.

What I claim as new and desire to secure by Letters Patent of the United States, is,—

1. The combination with a tank, of an inverted U-shaped tube having one leg inside 105 of said tank and the other leg outside, and a gage-tube communicating with said outside leg said inverted U-shaped tube being filled with liquid.

2. The combination with a tank, of an 110

inverted U-shaped tube having one leg inside of said tank and the other leg outside, a gage-tube communicating with said outside leg, and an upturned loop at the end of the 5 inside leg.

3. The combination with a tank for liquid, of a gage-tube outside the tank, and a tube communicating with the gage-tube at one end and depending into said liquid at the

other, the intermediate portion thereof rising 10 higher than the level of said liquid and being itself filled with liquid.

In witness whereof, I have hereunto set my hand this 12th day of September, 1906.

GEORGE E. MUSGROVE.
